ELECTRICAL WAVE TRANSMISSION
SYSTEM

Paul O. Farnham, Boonton, N. J., assignor, by
mesne assignments, to Radio Corporation of
America, New York, N. Y., a corporation of
Delaware

Application March 21, 1931, Serial No. 524,383

20 Claims. (Cl. 250—20)

This invention relates to electrical wave transmission systems, and particularly to systems employing diode rectifiers for demodulating carrier waves and/or for automatically regulating the gain of a vacuum tube amplifier.

It has been recognized that a diode rectifier may be so operated as to develop a direct current potential substantially proportional to the impressed carrier voltage, and use has been made of 10 this property to control the gain of an amplifier which precedes the diode rectifier.

Previous systems in which a diode detector has been used to furnish a direct current potential for the purpose of controlling amplification in the 15 preceding stages as well as to furnish an audio output for further amplification have been open to several objections. Satisfactory gain and selectivity from a circuit feeding the detector were difficult to obtain when the diode biasing resistor 20 was in shunt with the input circuit. Since the direct current potential for automatic volume control purposes was developed at low carrier levels on the detector the characteristic of the control suffered. That is, the action of the automatic volume control with increasing input to the 25 receiver was not sharp and did not hold the audio output substantially constant with increasing inputs. A further objection to previous automatic gain control systems has been that while the receiver was tuned to frequencies at which no strong 30 input signals were present, the greatly increased sensitivity of the system caused the amplified tube and circuit noise to be objectionable.

An object of the present invention is to provide 35 improved circuit arrangements for obtaining automatic volume control in electrical wave transmission systems of the type including a diode rectifier, and more particularly to provide circuit arrangements for increasing the efficiency of diode 40 rectifiers.

In the accompanying drawings, which illustrate certain specific embodiments of the invention,

Fig. 1 is a circuit diagram of a carrier wave receiver including a diode rectifier,

Fig. 2 is a curve sheet illustrating the relationship which may obtain between carrier input and rectified output in a rectifier such as shown in 45 Fig. 1,

Fig. 3 is a fragmentary circuit diagram of another embodiment of the invention, and

Fig. 4 is a curve sheet illustrating the relationship between the signal input to a receiver such as shown in Fig. 1, and the audio output of the receiver.

In Fig. 1 the reference numeral 1 identifies the 55 collecting structure which passes received carrier wave signals to the tuned input circuit, comprising inductance 2 and variable condenser 3, of a radio frequency amplifier tube 4. The amplified output from tube 4 is passed to a network, indi-

cated generically at 5, which may comprise a simple coupling impedance or may include additional amplifier stages.

The input impedance of the diode rectifier is coupled to the output terminals of the network 5 and, as illustrated in Fig. 1, the input impedance comprises an inductance 6 in series with a tuning condenser 7 and blocking condenser 8, the junction of the condensers being connected to ground and to the low potential output terminal of the network 5. The coupling to the network 5 may be of any appropriate type, a capacitive coupling through condenser 9 being illustrated as typical of one form.

As stated in the copending application of Knox 15 Charlton Black, Ser. No. 446,755, filed April 23, 1930, patented July 26, 1932, as U. S. Patent 1,869,089, any tube element in the electron field from a cathode will, irrespective of the operation 20 of the other tube elements, give satisfactory diode rectification in conjunction with the cathode, provided a small positive direct current voltage will cause appreciable current to flow to the electrode. According to the present invention, this principle of vacuum tube operation is utilized by 25 employing two or more tube elements as the anodes of substantially independent diode output circuits. With this arrangement it becomes possible to exercise a selective control over the development of each of the rectified voltages which 30 are to be obtained from the rectifiers. Furthermore, to simplify the construction of the output 35 circuits, the diode connections are "inverted", i. e., the high carrier potential terminal of the input circuit is connected to the diode cathode.

The multiple diode rectifier 10 may be, and 40 preferably is, a commercial triode of the type having a heater 11, an equipotential cathode 12, grid 13 and plate 14. For convenience of description, the electrode 13 will be referred to as the "grid", but it will be apparent from the following description that the grid 13 functions as the anode of a diode rectifier. The high potential 45 side of the tuned input circuit is connected to the cathode 11 and, so far as concerns carrier frequencies, the input circuit is completed to the rectifier anodes by the radio frequency by-pass condenser 15 which is connected between the grounded terminal of the input circuit and the grid, and the audio frequency by-pass condenser 16 which is shunted across the grid and plate 50 terminals.

The audio frequency output voltage is developed across resistive impedance in the circuit 55 between the grid 13 and cathode 12. The low carrier potential terminal of the inductance 6 is connected to ground through a resistance 17 and the audio output circuit of the rectifier includes the resistance 18, which, by an adjustable tap 19, may be connected to any desired point along the 60

resistance 17. The direct current output resistance 20 is connected between plate 14 and the grounded terminal of the resistance 17.

The opposite terminal of resistance 17 is connected by a lead 21 to a source of direct current potential which is positive with respect to ground, thus providing a drop of potential along resistance 17 which applies bias voltages E_1 , E_2 upon the anodes 13, 14, respectively, which are negative with respect to the cathode voltage.

The audio frequency voltage may be transferred to the audio amplifier through the blocking condenser 22 and voltage divider 23, the tap on the voltage divider being adjustable to regulate the output level of the receiver. The direct current voltage developed across resistance 20 may be returned to the amplifier tube 4 as an automatic gain control bias, the lead 24 from the diode plate 14 to the low potential terminal of the inductance 2 including a filter 25 for suppressing alternating components. The low potential terminal of inductance 2 is connected to the tuning condenser 3 through the blocking condenser 26, and the cathode circuit 25 of the amplifier includes a bias resistor 27 for supplying the normal, or maximum sensitivity, bias to the amplifier grid.

As is now customary, the several tuning elements of the receiver, i. e., the condensers 3 and 7, and any tuning elements which may be included in the network 5 are preferably connected mechanically for simultaneous adjustment, as indicated by the dotted line 28.

It is to be noted that the particular location 35 of the audio frequency by-pass condenser between the grid 13 and plate 14 is important in reducing the distortion in the audio frequency output voltage impressed across the impedance 23 when the impressed signal across the input 40 to the rectifier is just sufficient to establish a direct current voltage across the resistance 20. Resistance 18 should preferably be made smaller than resistance 20 for the same purpose.

The operation of the receiver, and particularly 45 that of the rectifier system, will be apparent from a consideration of the curves of Fig. 2. In the usual diode rectifier systems, no provision is made for applying steady bias potentials to the electrodes and a small flow of direct current 50 takes place even in the absence of any alternating current input.

Curve A shows the relation which would obtain between direct current output and carrier wave input voltage in the absence of a bias 55 potential E_2 . Similarly curve B illustrates the relationship between audio frequency output voltage and carrier input voltage in the absence of a bias voltage E_1 . Upon the application of the initial bias voltages, rectification in the respective 60 output circuits is postponed until the peak carrier voltage impressed upon the rectifier is approximately equal to the respective bias potentials. The relationships between carrier voltage and the direct current and audio frequency output voltages developed in the circuit of Fig. 1 are shown by curves A' and B', respectively.

By suitable choice of the bias E_2 , the development of a direct current output may be postponed until the signal energy available at the collector structure is sufficient, with maximum 70 amplifier gain, to bring the carrier input to the rectifier up to the value corresponding to the predetermined maximum audio frequency output level.

75 While this postponement of rectified direct

current output may be useful in various circuit arrangements, it is particularly effective in automatic gain control systems of the type represented in Fig. 1. By delaying the development of a rectified carrier voltage until the signal input reaches a definite value, the receiver sensitivity remains unchanged for all relatively weak signals but, with increasing signal strength, the gain control voltage developed by the rectifier becomes effective to hold the rectifier input voltage substantially constant.

Due to the high amplification usually obtained in receivers of the automatic gain control type, the output obtained when the amplifier is tuned to a frequency at which no, or only a weak, signal input is present is usually accompanied by a relatively high noise output arising in the tubes and circuits as well as static disturbances. By adjusting the diode bias potential E_1 to suppress all audio output for carrier voltages below a magnitude necessary to give an audio signal free from noise disturbances under normal operating conditions, this noisy audio frequency output can be eliminated.

When the direct current source that supplies current to the resistor 17 is not sufficiently free from alternating components, as might be the case when the direct current is obtained by rectification of alternating current from the house lighting system, it is possible that the circuit shown in Fig. 1 will impress an objectionable "ripple" voltage upon the grid of the first audio amplifier. This objection may be overcome, as shown diagrammatically in Fig. 3, by connecting the cathode of the amplifier to such a point on resistance 17 that the ripple voltage drops to negligible magnitude.

As illustrated in Fig. 3, the lead 29 from the cathode of the first audio amplifier 30 is not so connected as to eliminate all ripple voltage, but is connected to the high (direct current) terminal of resistance 17. The remaining elements of the circuit may be substantially identical with the corresponding elements of Fig. 1, and are identified by the same reference numerals. While 45 this arrangement does impress upon the first audio amplifier the alternating current component present in the relatively low direct current voltage E_1 , this ripple voltage will usually be too small to create any disturbing effect when 50 the rectified power supply has been filtered to a degree satisfactory for energization of the plate circuits of the several tubes of the receiver. The arrangement has the decided advantage that the plate voltage applied to the audio amplifier 55 30 may be so chosen that the direct current drop E_1 furnishes an appropriate potential for the audio amplifier.

Although the invention is not limited to any particular circuit constants, the following tabulation is cited as illustrative of values which have given satisfactory performance.

Capacities 8, 16=0.1 microfarad	60
Capacity 15=100 micromicrofarads	65
Resistance 18=200,000 ohms	
Resistance 20=2 megohms	
Voltage E_2 =40 volts	
Voltage E_1 =7 volts	
Capacity 22=0.1 microfarad	70
Resistance 23=500,000 ohms	
Filter 25=500,000 ohm resistances and 0.1 microfarad capacities	

Certain advantages obtainable by use of the invention will be apparent from a consideration 75

of the curves of Fig. 4. The relation between the audio output and signal input for an automatic gain control receiver of the type including a conventional arrangement of diode rectifier (i. e. without fixed bias voltages on the diode) is shown by curve C. It will be noted that the sensitivity of the radio amplifier is seriously affected for weak signals and that the audio output continues to rise with increasing input signal strength even when the maximum possible control is effective.

When the operation of the automatic gain control is deferred by the application of an initial bias voltage E_2 , there is no reduction in sensitivity for weak signals and the relationship between audio output and signal input is represented by the curve D. The data from which this curve was plotted was obtained when the circuit elements of Fig. 1 were not adjusted to cause any postponement of audio output. The operation resulting when an initial bias E_1 is applied in the audio output circuit of the double diode is represented by curve F. The shaded area to the left of the lower branch of curve F indicates the range of input signal strength for which disturbing noises will mask the audio signal or will be present to such an extent that satisfactory reproduction is not possible. By providing a sharp cut-off at this lower range of input voltages, these noises will be completely suppressed and a constant audio output level will obtain for substantially all signals.

So far as concerns the present invention, it is to be understood that the illustration of a single stage of tuned radio frequency amplification in Fig. 1 is but illustrative of one type of circuit with which the invention may be employed. The principles as above outlined may, of course, be employed in connection with any of the known automatic gain control circuits such, for example, as cascaded stages of radio or intermediate frequency amplification or the first detector in the case of a superheterodyne receiver. Furthermore, the multiple-diode rectifier may be employed for other purposes and with circuits other than those of automatic gain control systems.

While the invention permits the use of a tunable input circuit for the rectifier, it is possible to employ an untuned input impedance. The customary arrangement in which the low potential side of the input circuit is connected to the rectifier cathode may be employed by providing an appropriate by-pass system in the connections from the high potential side of the input circuit to the rectifier anodes.

I claim:

1. A combined demodulator and carrier voltage rectifier, comprising a double diode having a cathode and two anodes; an input impedance comprising an inductance shunted by a tuning condenser in series with a blocking condenser, a connection from the junction of the inductance and tuning condenser to the rectifier cathode, a connection from the junction of the condensers to ground, and resistive output impedances connected between the respective anodes and ground, capacity by-passing one output impedance for carrier frequency and the other for audio frequency, and a source of direct current and adjustable means for establishing direct current bias potentials between the rectifier elements.

2. The invention as set forth in claim 1 wherein the capacity which by-passes one output impedance for audio frequency currents is connected across the two anodes of said rectifier.

3. In an alternating current amplifier, the combination with a vacuum tube amplifier, input and output circuits therefor, and means normally biasing said amplifier to secure a desired amplification of received alternating currents, of a diode rectifier, an input impedance coupled to the amplifier output circuit and effectively connected between the rectifier cathode and anode, an output resistance effectively between the rectifier cathode and anode, a second diode rectifier, coupled to said input impedance, and including an audio frequency load in its output, means preventing the development of rectified potential across said resistance until the alternating current voltage across said rectifier input impedance exceeds a predetermined value, and additional means preventing said second diode from rectifying alternating current voltages below a desired magnitude.

4. The invention as set forth in claim 3, wherein said first preventing means comprises a source of potential establishing upon the first rectifier cathode a more positive direct current potential than that of the first rectifier anode.

5. In a modulated carrier wave receiver, the combination with a carrier wave amplifier of the audion type, and means impressing a direct current bias upon a grid of said audion, of a diode rectifier having a cathode and a pair of anodes, a tuned input circuit having its high carrier potential terminal connected to the rectifier cathode, means coupling said input circuit to the output circuit of said amplifier, means grounding the low carrier potential terminal of said tuned input circuit, individual resistances connecting the respective anodes to ground, capacity by-passing one of said resistances for carrier frequencies, a circuit for transferring back to the amplifier audion grid the direct current potential developed across the other resistance, and a source of potential establishing upon the rectifier cathode a more positive direct current potential than that of one of said anodes.

6. In an automatic gain control receiver, the combination with means for amplifying received signals, a demodulator providing an audio current, means for amplifying the audio current, and means automatically controlling the gain of said signal amplifying means as a function of received signal energy, of means rendering said demodulator inoperative for impressed voltages of less than a predetermined magnitude, and additional means rendering said gain controlling means inoperative for all values of received signal voltages of less than a predetermined magnitude.

7. In a transmission system, the combination with a signal frequency amplifier, a demodulator, an audio frequency load circuit working out of said demodulator, and means including a rectifier for automatically varying the gain of said amplifier to compensate for variations in the strength of received signals, of means for postponing operation of said rectifier until the received signal strength exceeds a predetermined value, and means for reducing the audio frequency distortion arising from the distortion of the form of the amplified signal wave impressed upon said demodulator when said rectifier becomes operative.

8. In a transmission system, the combination with a signal frequency amplifier, a demodulator, and an automatic gain control system operative only when the strength of the received signal wave exceeds a predetermined value to vary the

amplifier gain automatically to compensate for fluctuations in the strength of received signal waves, said system including a rectifier which distorts the form of the amplified signal wave impressed on said demodulator, of means for reducing the audio frequency distortion arising from said distortion of the wave form.

9. In a transmission system, the combination with a signal frequency amplifier, a demodulator, 10 an audio frequency load circuit working out of said demodulator, and means including a rectifier for automatically varying the gain of said amplifier to compensate for variations in the strength of received signals, of means for postponing operation of said rectifier until the received signal strength exceeds a predetermined value, and condensive means for reducing the audio frequency distortion arising from the distortion of the form of the amplified signal wave 20 impressed upon said demodulator when said rectifier becomes operative.

10. In combination with a signal amplifier comprising a tube having a tuned input circuit, a following tube including a cathode and at least 25 one anode and a grid electrode, means for maintaining the anode and grid electrode at different direct current potentials with respect to the cathode; a tuned input circuit connected between the cathode and anode of said following 30 tube and including a resistor for developing a direct current voltage from signal energy impressed on said second circuit, a control connection between an input electrode of said amplifier and said resistor, means for connecting said grid 35 to a point in said second tuned circuit, and a signal transmission network coupling the second tuned circuit to the amplifier output.

11. In a system as defined in claim 10, said grid connecting means being adjustable, and an 40 audio amplifier tube having its control grid coupled to a path including said following tube grid.

12. In a system as defined in claim 10, an audio 45 amplifier tube, and means for adjustably coupling the control grid of the latter tube to a path including said following tube grid.

13. A rectifying system including a source of 50 alternating current, a thermionic rectifier having a plurality of rectifying anodes connected to said source, an output circuit of said rectifier connected to one of said anodes and including means for producing therein a rectified voltage substantially equal to the peak of the unrectified voltage applied to said rectifying system and also including a second independent output circuit 55 of said rectifier connected to another anode thereof and including therein a fixed voltage source, the rectified voltage produced in said second output circuit being effective only when the peak of the unrectified voltage applied to said rectifying system exceeds said fixed voltage.

14. A radio receiving system including a common source of signal-bearing radio frequency current and means for separating said current into a plurality of paths, means in one path for 65 acting upon said radio frequency current so as to yield direct current for automatic volume control only when said radio frequency current exceeds a given minimum value, and means in the other path for yielding an audio frequency output 70 only when said radio frequency current exceeds a given minimum value.

15. In a carrier wave receiver, a carrier frequency amplifier and an audio frequency amplifier, a detector interposed between said amplifiers and comprising within a single envelope an elec- 75

tron emitting cathode and two anodes, an input impedance having one end connected to said cathode, a load circuit connected between one end of said input impedance and one of said anodes, said load circuit being responsive to the 5 audio frequency component of the demodulation products generated by said detector, a source of bias potential in series with said load circuit and making the anode to which said load circuit is connected negative with respect to said cathode, 10 a second load circuit connected between the end of said impedance to which said first load circuit is connected and the other of said anodes, said load circuit being responsive to the direct current component of said demodulation 15 products, a source of bias potential in series with said second load circuit and making the anode to which said second load circuit is connected negative with respect to said cathode, said first 20 load circuit supplying voltages to actuate said audio frequency amplifier and said second load circuit supplying voltages for automatic gain control of said carrier frequency amplifier.

16. In an electrical wave transmission system, 25 a double diode rectifier tube having a cathode and two anodes, a single input impedance connected between the cathode and anode of said rectifier, and circuit elements connected to the respective anodes to constitute two substantially independent output circuits for said rectifier, 30 in combination with a source of direct current potential establishing negative bias potentials upon the respective anodes, thereby to prevent rectification in the respective output circuits until the alternating voltage across said input 35 impedance exceeds predetermined minimum values.

17. In a modulated carrier wave receiver, the combination with a carrier wave amplifier, of a 40 diode demodulator for demodulating the carrier waves amplified by said amplifier, and a background noise suppression device means establishing upon the diode cathode a positive bias potential of such magnitude with respect to the anode of said diode that demodulation is prevented 45 until the carrier voltage impressed upon said diode exceeds substantially the magnitude of said impressed bias potential, a second diode circuit for developing a direct current voltage from said waves, means for applying said last voltage to 50 the amplifier for regulating the gain thereof, and both said diodes being provided by a single tube having a single cathode and a pair of anodes receiving electrons therefrom.

18. In a receiving system, a tube provided with 55 a cathode and at least two cold electrodes, a tuned signal input circuit connected between the cathode and one electrode, a connection between the other electrode and said input circuit, a signal transmission tube, a gain control connection between the signal transmission tube and solely said one electrode, a demodulated signal path including a tube coupled to said other electrode, said other electrode consisting of a grid, and a direct current connection between 60 the cathode of the last tube and a point on the circuit connecting the cathode and grid electrode of the first tube.

19. In a carrier wave receiver, a carrier frequency amplifier and an audio frequency amplifier, a detector interposed between said amplifiers and comprising within a single envelope an electron emitting cathode and two anodes, an input impedance having one end connected to said cathode, a load circuit connected between one end 70

5 of said input impedance and one of said anodes, said load circuit being responsive to the audio frequency component of the demodulation products generated by said detector, a second load circuit connected between the end of said impedance to which said first load circuit is connected and the other of said anodes, said load circuit being responsive to the direct current component of said demodulation products, a 10 source of bias potential in series with said second load circuit and making the anode to which said load circuit is connected negative with respect to said cathode, said first load circuit supplying voltages to actuate said audio frequency 15 amplifier and said second load circuit supplying voltages for automatic gain control of said carrier frequency amplifier.

20. In a carrier wave receiver, a carrier frequency amplifier and an audio frequency amplifier, a detector interposed between said amplifiers and comprising within a single envelope an

electron emitting cathode and two anodes, an input impedance having one end connected to said cathode, a load circuit connected between one end of said input impedance and one of said anodes, said load circuit being responsive to the audio frequency component of the demodulation products generated by said detector, a source of bias potential in series with said load circuit and making the anode to which said load circuit is connected negative with respect to said cathode, 10 a second load circuit connected between the end of said impedance to which said first load circuit is connected and the other of said anodes, said load circuit being responsive to the direct current component of said demodulation products, 15 said first load circuit supplying voltages to actuate said audio frequency amplifier and said second load circuit supplying voltages for automatic gain control of said carrier frequency amplifier.
